PASTE TUBE CLOSURE

Albert A. Rue, Beaver, Wash.

Application April 18, 1939, Serial No. 268,562

3 Claims. (Cl. 221—60)

The present invention relates to closures for tooth paste tubes and the like and has for its primary object to provide an upstanding discharge neck for the tube having a discharge opening therein and provided with a closure slidably mounted over the neck for controlling passage through the discharge opening and providing operating means for said closure in the form of a ring operable by a rotary movement to actuate the sliding closure.

A further object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which—

Figure 1 is a fragmentary side elevational view of a paste tube showing the closure mounted in position on the neck of the tube.

Figure 2 is a similar view taken substantially at right angles from Figure 1.

Figure 3 is a top plan view.

Figure 4 is a vertical sectional view.

Figure 5 is a transverse sectional view taken substantially on a line 5—5 of Figure 1, and

Figure 6 is a detail showing the pin and slot connection between the sliding closure and the rotary operating ring.

Referring now to the drawing in detail, wherein for the purpose of illustration I have disclosed a preferred embodiment of the invention, the numeral 5 designates a conventional type of paste tube having a discharge neck 6 rising therefrom, the neck embodying two flat parallel side walls 7 and a rounded top 8 merging with the remaining side walls 9. The top of the rounded portion of the neck is formed with a discharge opening 10.

The edges of the side walls 9 are formed with parallel guide ribs 11 extending over the rounded top 8 and slidably positioned in the channel between the guides is a closure 12, preferably constructed of metal and in ribbon form and curved in conformity to the rounded top 8, the ends of the closure extending in substantial parallelism against the sides 9 as more clearly shown in Figure 4 of the drawing.

The closure 12 is provided with a slotted open-

ing 13 adapted to register with the opening 10 by the sliding movement of the closure across the rounded top of the neck.

Surrounding the base of the neck is a ring member 14 having an internal arcuate slot 15 at diametrically opposite sides and within each of the slots is positioned a pin 16 projecting outwardly from the end portion of the closure 12. The slots are of opposite inclination.

Accordingly, it will be apparent that upon the rotation of the ring member 14 around the neck that the arcuate slots 15 by reason of their engagement with the pin 16 will cause the closure 12 to slide transversely across the top of the neck to move the openings 10 and 13 into and out of registering position.

It is believed the details of construction and manner of operation of the device will be readily understood from the foregoing without further detailed explanation.

Having thus described the invention what I claim is—

1. A paste tube closure comprising in combination a paste tube having a neck provided with a rounded extremity and having a discharge opening therein, a closure mounted for sliding movement across the rounded end of the neck and having an opening therein adapted to register with said first named opening, the ends of the closure extending downwardly along the side of the neck and a rotatable member carried by the neck and having operative engagement with the opposite ends of said closure to slidably actuate the closure.

2. A paste tube closure comprising a neck on the tube having a discharge opening, a guide channel on the neck extending across the top thereof, a closure slidable in the channel for controlling the opening, a ring rotatably mounted on the neck and having opposite inclined slots in diametrically opposite sides and pins carried by the closure and engaged in said slots to slidably actuate the closure.

3. A paste tube closure comprising a neck on the tube having a discharge opening, a guide channel on the neck extending across the top thereof, a closure slidable in the channel for controlling the opening, pins carried by the closure and a ring rotatably mounted on the neck and having oppositely inclined slots receiving the pins and adapted to slidably actuate the closure upon a rotary movement of the ring.

ALBERT A. RUE.
